RECORDER

Charles F. Wallace, Westfield, N. J., assignor to Wallace & Tiernan Products, Inc., Belleville, N. J., a corporation of New Jersey

Application December 26, 1940, Serial No. 371,618

19 Claims. (Cl. 234—36.5)

This invention relates to recorders of the time interval type, especially adapted for use for recording the signals transmitted by radiometeorograph transmitters of the time interval type, such as, for example, the radiometeorograph transmitter of my patent application Serial No. 327,767, filed April 4, 1940, the recorder operating in response to electric current impulses from a radio receiver receiving the radio signals, which may be radio impulses or interruptions in an otherwise continuous radio signal. The new recorder is also adapted for use in other time interval telemetering systems wherein the measurement to be recorded is indicated by the time interval between a synchronizing reference impulse or signal and the signals, or impulses, representing the measurement transmitted; and it is particularly adapted to such systems in which driving motors of the transmitter and the recorder cannot be supplied with synchronous alternating current or be otherwise controlled to maintain absolute uniformity of speed between the motors.

The invention aims to provide an improved time interval recorder having a high speed of operation and great accuracy as compared to such recorders heretofore known, and which is reliable in operation and may be made of an over-all size and weight to be readily portable; to provide a recorder having means for readily synchronizing the speed of its operating motor with that of the motor of the distant transmitter whose signals are being recorded; to provide a recorder having a stylus which makes only a dot, or mark of minimum length, on the chart regardless of the length of the transmitted signal or impulse, and which is not readily susceptible to operation by spurious impulses; to provide a recorder in which the chart or record sheet is advanced only during the return, or non-printing, stroke of the stylus; to provide a recorder in which either a flat chart or a rolled chart may be used; to provide means for framing the record, that is, adjusting to position the index marks on the chart; to provide a recorder having no relays, motors or other mechanism other than a single motor for advancing the paper and moving the stylus carriage forward and returning it to its initial position at the end of each sweep of the stylus carriage, and a single magnet for giving the stylus arm its synchronizing and printing strokes; to provide means for the rapid return stroke of the stylus carriage, thus making possible the receipt of more signals in a given time; to provide a recorder making a record which is immediately

visible to the operator; and to provide a recorder which is portable and light in weight and yet rugged in construction and durable, and especially suited to the rigors of military and similar service. Other objects and advantages of the new recorder will appear from the following description.

The invention consists in various features of construction, arrangement and combinations of parts whereby the objects and advantages of the invention are attained, all as will be clearly disclosed by the following description in connection with the drawings and specifically pointed out in the claims.

A full understanding of the invention can best be given by a detailed description of a recorder embodying the various features of the invention in the form now considered best, and such a description will now be given in connection with the accompanying drawings illustrating a portable recorder especially adapted for military and similar service. In said drawings—

Fig. 1 is a plan view of the apparatus as it appears with the cover of the cabinet opened to stand upright and shown in section;

Fig. 2 is a view in elevation of the parts of the apparatus which are mounted on the under side of the hinged mounting plate, the plate having been swung up out of the cabinet to stand vertical;

Fig. 3 is a sectional view on a larger scale than Figs. 1 and 2 taken on line 3—3 of Fig. 1;

Fig. 4 is a sectional view on a slightly larger scale than Fig. 3 taken on line 4—4 of Fig. 1;

Fig. 5 is a sectional view taken on line 5—5 of Fig. 1;

Fig. 6 is a sectional view taken on line 6—6 of Fig. 4;

Fig. 7 is a sectional view taken on line 7—7 of Fig. 3;

Fig. 8 is a sectional view taken on line 8—8 of Figs. 2 and 9;

Fig. 9 is a sectional view taken on line 9—9 of Fig. 8;

Fig. 10 is a sectional view taken on line 10—10 of Fig. 9; and

Fig. 11 is a wiring diagram.

Referring to the drawings, the various parts of the apparatus are mounted on a mounting plate 10 which is hinged to the rear wall of a cabinet 11 which has a cover 12 also hinged to its rear wall. Mounted beneath the plate 10 is a paper feed roller 15 which extends upward through a slot 16 in the mounting plate with its upper surface substantially flush with the upper

surface of the plate. The roller is journalled in bracket plates 17 and 18 which extend vertically downward from the mounting plate. The roller is turned manually for adjusting the record sheet, or chart, by means of a finger knob 20 on a shank which extends through the mounting plate and is rotatable therein and has fast on its lower end beneath the mounting plate a bevel gear 21 meshing with a bevel gear 22 fast on the stub shaft 23 which extends from the left hand end of the roller as viewed in Figs. 2 and 5.

The paper is pressed against the feed roller by pressure rolls 25 carried by spring arms extending from a support bar 26 which is pivotally mounted at its ends in bracket plates 27 and 28 so that the bar may be rocked by means of a finger piece 29 to raise the rolls 25 from the paper. A spring 30 connected to a rod 31 extending from the bar downward through an opening in the mounting plate normally holds the bar rocked and under tension to press the rolls 25 against the paper or record sheet on the feed roller. The feed roller has most desirably a knurled or otherwise roughened zone 32 beneath each of the pressure rolls 25. Mounted in front of and extending parallel to the feed roller is a long small-diameter hold-down roller 33 which is journalled by having its reduced ends extend into vertical slots 34 in the bracket plates 27 and 28, one of said slots being shown in Fig. 3. The roller is thus free to rest by gravity on the paper as it advances from the feed roller.

The paper feed roller 15 is given a step-by-step feeding movement by a gear 35 mounted on the shaft 23 of the roller between a shoulder on the shaft and a spring spider 36 mounted fast on the shaft and which presses the gear 35 against the shaft shoulder, the gear being thus frictionally connected to turn the feed roller for feeding the paper but permitting the roller to be turned manually by means of the finger knob 20 without turning the friction gear 35. The gear 35 is driven by a pinion 37 on a shaft which carries a worm gear 38 meshing with a worm 39 on a shaft 40. Shaft 40 is turned for giving the roller 15 its step-by-step paper feeding movement by means of a pulley wheel 41 which is one of the guide pulleys for the cord which reciprocates the stylus carriage as hereinafter described. This pulley 41 is free to turn on the shaft 40 but carries a pawl 42 engaging a ratchet wheel 43 fast on the shaft, whereby when the pulley is turned in the direction indicated by the arrow in Fig. 5, the shaft 40 is turned. When the pulley rotates in the opposite direction, the pawl 42 slips over the ratchet wheel and the shaft is held against turning in the opposite direction by a back stop pawl and ratchet 44. Pulley 41 turns in the direction indicated by the arrow during the return, or non-printing, strokes of the stylus, and turns in the opposite direction during the printing strokes of the stylus. The chart is thus stationary during all printing strokes of the stylus, and is advanced only during the non-printing return strokes of the stylus.

When charts in the form of separate sheets are used, they are merely entered from the rear over the feed roller and beneath the pressure rolls 25. When the charts are printed on a long sheet or web which comes rolled on a tube, the paper, or chart, roll 45 is supported beneath the mounting plate on flanged short cylindrical roll supports 46 and 47 which extend into the ends of the hollow roll in the customary manner. One of the roll supports, the support 46 at the right-

hand end of the apparatus as viewed in Fig. 2, is journalled on a stub axle 48 and pressed toward the left by a spring 49 between the end of the roll support and a collar on the stub axle, the 5 stub axle being screw-mounted in the bracket plate 17 and locked by means of a lock nut as shown in Fig. 7. The roll support 47 at the other or left-hand end of the apparatus is journalled on a stub axle 50 which is screwed into a bearing sleeve 51 set in the bracket plate 18 and which carries a finger knob 52 whereby the stub axle may be withdrawn for removal and replacement of the chart rolls. The paper is threaded beneath and upward about the feed roller 15 and 10 through the slot 16 in the mounting plate and forward over the feed roller and beneath the hold-down rollers 25 and 33. A drag spring 53 bears against the paper roll to prevent over movement.

20 The printing stylus is carried by a carriage 60 which is mounted to slide back and forth on a track or slideway formed by two parallel bars 61 and 62 connected by end plates 63 and 64, the slideway unit thus formed being mounted to rock on hollow studs 65 and 66 fixed in the bracket plates 27 and 28, respectively. The stylus carriage, as shown, is formed by a metal plate slidably hung on the rod 61 by upwardly extending ears 67 and extending beneath the rod 62 and 25 then further forward forming an arm 68 which carries the stylus at its forward end. In the normal position of the rocker slideway unit, the stylus carriage takes the position shown by dotted lines in Fig. 3, the stylus arm being pushed up 30 by a spring-pressed lifting pin 70 mounted in a holder 71 carried by the stylus arm, the pin being urged downward by a spring 72 to bear against the chart and push the stylus arm upward, thereby holding the stylus carriage in position with the pen or other stylus point raised clear of the 35 chart as shown in Fig. 3.

When the slideway unit is rocked from its normal position, shown by dotted lines in Fig. 3, to the position shown in Fig. 4, the rear end of the 40 carriage is raised by the rod 61 and the rod 62 engages the carriage to throw the stylus arm downward against the comparatively light pressure of the spring 72. The rocking movement of the slideway is not sufficient to carry the pen 45 or stylus point down into contact with the chart, but by the inertia of the stylus arm and parts carried thereby the movement of the stylus arm is continued to move the stylus point into contact with the paper, the carriage plate turning 50 on rod 61 somewhat down away from the rod 62 as shown in Fig. 4. The stylus arm and carriage 55 are then immediately lifted by the lifting pin 70 to raise the stylus clear of the chart as shown in Fig. 3, the carriage plate then coming into engagement with the rod 62 if the slideway unit 60 has not been immediately rocked back to its normal position. The stylus thus makes only a momentary contact with the chart and prints only 65 which the slideway unit is rocked from its normal position and of the traversing movement of the stylus carriage.

Instead of a stylus of the non-printing type 70 making its marks by pressing a carbon sheet or ribbon against the chart, a printing stylus is most desirably used and preferably an ink printing stylus, or pen. The pen may be of any suitable form. As shown, the pen 73 extends out through a feed opening at the bottom of an ink reservoir 74 mounted at the end of the stylus

arm, the pen point being the lower end of a feed spring 75. The mounting plate has, most desirably, an inlaid platen strip 76 of semi-hard rubber or leather or other suitable material extending longitudinally beneath the path of the pen.

The slideway unit is rocked between its normal pen-raised position shown by dotted lines in Fig. 3 and its printing position shown in Fig. 4 by the armature 77 of an electromagnet 78, the armature being connected by a link 80 to a stud 81 extending from the end plate 63 of the slideway unit. The armature 77 is normally retracted by a spring 82 to rock and hold the slideway unit in its normal raised-pen position shown in Fig. 3. To provide for adjusting the extent of the downward throw of the pen arm, the link 80 is connected at its armature end to a plate 83 which is under spring tension to move away from the armature and is held in adjusted position by an adjusting screw 84.

The stylus carriage 60 is moved back and forth on the slideway by means of a cord 90 which extends from the carriage through the hollow stud 65 to a guide pulley 91 at the extreme right hand end of the machine as viewed in the drawings, thence downwardly to a helically grooved driving drum 92 about which the cord makes several turns. From the driving drum, the cord extends to the guide pulley 41 and thence upward to and around a guide pulley 93 from which it extends through the hollow stud 66 to the stylus carriage. The two ends of the cord are connected to a split post 94 extending upward from the carriage plate, and for maintaining the cord under suitable tension a spring 95 is connected between the post 94 and the end of the cord at the left hand side of the post. The drum 92 is turned at a predetermined speed to move the stylus carriage to the right, as viewed in the drawings, to give the stylus its forward, or printing, movement across the chart, and when the carriage has completed this printing movement, the drum is rotated rapidly in the opposite direction to cause a quick return non-printing movement of the carriage to the left, back to its extreme left hand position.

The drum is driven in the direction of the arrow in Fig. 7 for giving the stylus carriage its printing traversing movement across the chart by a motor-driven shaft 100 which is constantly driven and which drives the drum through mechanism shown in Figs. 2, 3, 8, 9 and 10, which will now be described.

In the apparatus shown, and most desirably, the motor 101 which drives the shaft 100 is a governor-controlled, series type electric motor driving the shaft through a reduction gear unit 102. A pinion 103 on shaft 100 drives a large gear 105 mounted fast on a shaft 106 which extends between and is journalled in plates 107 and 108 extending downward from the mounting plate 10. Also mounted on the shaft 106 but free to turn thereon is a pinion 111 having mounted fast on its hub a disc 110, the disc and pinion being positioned on the shaft between the gear 105 and a collar 112. The disc and pinion are frictionally driven by the gear 105 through a U-spring 113 the two arms of which lie in a groove in the periphery of the disc 110 and are under tension to press into said groove, one arm of the U-spring being curved for positioning the spring on the friction disc. A pin 115 extending from the side of gear 105 serves by engage-

ment with the inner side of the end of the curved arm to cause the U-spring to rotate with the gear as the gear rotates in the direction of the arrow in Figs. 8 and 10.

5 The disc 110 and pinion 111 are thus by the frictional engagement of the arms of spring 113 in the groove of the disc caused to turn with the gear 105 when the load on the pinion is not great enough to overcome this friction drive. When 10 the rotation of the pinion is sufficiently resisted, however, the spring arms slip on the disc, sliding in the groove of the disc to provide a smooth uniform tension on the disc and parts driven thereby. When the pinion is again free from the 15 opposing resistance, or load, it is again driven by gear 105 through the U-spring.

The pinion 111 engages a gear 120 which is mounted fast on a shaft 121 journalled in the plates 107 and 108. A sleeve 122 free to turn on shaft 121 has fast thereon at one end thereof a gear 123 and has connected to it at its other end the inner end of a coiled spring 124, the outer end of which is connected to an anchor stud 125. The spring tends to rotate the gear 123 in anti-clockwise direction as viewed in Figs. 8 and 10, that is, as indicated by the arrow *b* in Figs. 8 and 10, in the direction opposite to that in which the gear 120 rotates. The gear 123 is turned against the tension of spring 124 by gear 120 from a starting position shown in Fig. 8 for nearly one complete rotation, and is then released and is returned rapidly by spring 124 to its starting position. To accomplish this, gear 120 has on its side toward gear 123 a driving dog 126, and gear 123 has on its side toward gear 120 a pivoted latch 127 which has an arm from the end of which a stop pin 128 extends through an opening 129 in gear 123, the opening being of such dimension greater than the width of the stop pin as to permit a limited pivotal movement of the latch between an engaging position as shown in Fig. 8 in which the end of the latch lies in the path of movement of the driving dog and a free position as shown in Fig. 10 in which the latch is out of the path of the driving dog.

40 When gear 123 has been returned to starting position, latch 127 is in its engaging position as shown in Fig. 8, to be engaged by dog 126 so that as gear 120 rotates gear 123 is turned with it until the stop pin 128 comes into engagement with the side of an arm 130. By this engagement with the arm 130, pin 128 is by continued movement of gear 123 shifted from one side to the other side of the hole 129, thereby shifting the latch 123 to its free position clear of dog 126 as shown in Fig. 10, gear 123 being thus released from gear 120 and its rotation stopped. Gear 123 then immediately makes a quick return movement under influence of the spring 124 back to its starting position, in which position it is 45 stopped by engagement of pin 128 with the arm 130, and the shifting of the pin across the opening 129 into engagement with the opposite side of the opening, the latch by this movement of pin 128 being shifted back to its engaging position to be again engaged by the driving dog as it comes around.

45 For cushioning the stopping of the quick return movement of gear 123 and parts driven by it, the arm 130 is pivotally mounted on sleeve 122 and has its outer end pivotally connected to the piston rod of a dash pot 131. During the forward turning of gear 123 by gear 120, arm 130 is turned by a spring 132 from the position shown 50 in Fig. 8 to that shown in Fig. 10 to withdraw the

dash pot piston. A screw 133 serves as an adjustable stop for limiting this return movement of the arm 130, thus determining the position to which the arm returns during the forward rotation of gear 123, and this position of the arm determines the point in the forward rotation of gear 123 at which it is released from gear 120, thereby determining the extent of the forward traversing movement of the stylus carriage, as will appear.

Gear 123 drives a pinion 135 on the shaft of the cord drum 92, the gear and pinion being of such relative size that the rotation of the drum by the forward and return rotations of the gear causes the desired traversing movements of the stylus carriage back and forth across the chart, the carriage being given its forward traversing movement when the gear 123 is driven by gear 120, and being given its quick return movement when gear 123 is released from gear 120 and given its return rotation by spring 124.

After the stylus carriage has been given its quick non-printing return movement, it is held against forward movement, that is, movement to the right in Figs. 1, 5 and 6 until released as the result of the receipt of a starting, or reference, signal from the transmitter whose measurements are being recorded. The stylus carriage is so held by a latch 140 extending from a member 141 mounted on the bracket 28 which drops over a latch dog 142 on the stylus arm of the carriage as the carriage comes to the end of its return movement. The latch by engagement with dog 142 holds the carriage against forward movement from its starting position until a starting signal causes magnet 78 to be energized to rock the slideway unit and tilt the stylus carriage to cause a reference mark to be made on the chart, and by this rocking movement of the carriage the latch dog is moved down out of engagement with the latch and the carriage is thereby released.

During the time that the stylus carriage is being given its quick return movement by the return rotation of gear 123, gear 120 has been continuing its rotation. After return movement of gear 123 has been completed and the stylus carriage thereby returned to its extreme left hand position, the driving dog 126 by continued rotation of gear 120 comes into engagement with the latch 127 on gear 123. Gear 123 will then be moved by gear 120 to cause such forward movement of the carriage as may be permitted by the latch 140, the latch dog 142 having been carried by the return movement of the carriage slightly beyond its latch engaging position. When the latch 140 is in holding engagement with the latch dog, however, forward movement of the carriage and thereby forward rotation of gear 123 are prevented. The friction clutch between driving gear 105 and disc 110 formed by the U-spring 113 then permits gear 105 to continue its rotation. Immediately, however, upon the rocking of the slideway unit upon receipt of an indexing signal and the resulting release of the stylus carriage, the friction disc and its driving pinion 111 are again turned by the gear 105 to drive the gear 120, by which gear 123 is then driven to cause forward movement of the stylus carriage.

The latch-carrying member 141 is adjustably mounted on the bracket 28 by means of a screw 145 extending from the bracket and threaded into the member and which may be turned by means of a knurled knob 146, turning the knob

thus adjusting the latch 140 in the direction of movement of the stylus carriage on the slideway. This adjustment of the latch determines the position in which the stylus carriage is held by the latch, that is, its starting position, and thus constitutes a margin adjustment means for determining the position on the chart of the index, or reference, markings.

For adjusting the tension of the spring 124 by which the gear 123 is rotated to give the stylus carriage its return movement, the anchor stud 125 is carried by an adjusting disc 150 fast on a block 151 rotatably set in an opening in the plate 107 and in which one end of shaft 121 has its bearing. The adjusting disc lies against the inner side of plate 107 and a friction plate 152 is secured to the block 151 by screws 153 and extends beyond the block to bear against the outer side of plate 107. The edge of disc 150 is toothed or otherwise roughened and is accessible at the lower edge of plate 107 (see Fig. 7) for turning the disc. By turning the disc, the tension of spring 124 may be increased or reduced as desired. The disc is clamped in adjusted position by a screw operated clamp 154 (Fig. 4).

The operation of the apparatus is briefly as follows: Assuming that the recorder is connected to a radio receiver receiving signals from a radiometeorograph transmitter which in each cycle of operations transmits first a reference, or starting, signal, then one or more signals indicating atmospheric conditions, and finally two closely spaced motor-speed indicating signals; and assuming that the on-and-off switch 155 of the apparatus is in the "on" position, and that the stylus carriage is at its starting position held by the framing latch 140: The stylus carriage having been held manually by the operator until there is a double click of magnet 78, then by the next impulse from the radio receiver, resulting from the reference, or starting, signal from the radiometeorograph transmitter, magnet 78 is energized to rock the stylus carriage, thereby releasing the carriage from latch 140 and causing an indexing, or reference, dot to be made on the chart by the stylus. The stylus carriage then immediately starts on its printing stroke across the chart, and as each signal impulse from the radio receiver energizes magnet 78 during the printing stroke, the carriage is rocked to cause the stylus to make a dot on the chart at a distance from the reference dot corresponding to and showing the time interval between such signal and the starting signal which caused the reference dot; and just before the carriage reaches the end of its printing stroke, it is rocked to make two closely spaced dots by the impulses resulting from the motor-speed-indicating signals sent by the transmitter. The driving motor will have been adjusted to operate at a speed to cause the stylus carriage to make its traversing movements approximately in synchronism with the operating cycles of the transmitter. With the motor so operating, just after the motor-speed-indication has been recorded on the chart, gear 123 is released from gear 120 by the rocking of its latch 127, and thereupon, by the rapid reverse rotation of gear 123 by spring 124, the stylus carriage is rapidly returned to its starting position and becomes again locked by the framing latch 140. During this return stroke of the stylus carriage, the paper is advanced one step and then remains stationary until the next return movement of the carriage. After being re-

turned to its starting position, the carriage remains stationary until magnet 78 is again energized by the starting reference signal at the beginning of the next cycle of operations of the transmitter.

By the adjustment of the framing latch 140 by means of the knob 146, the starting position of the stylus carriage may be adjusted to cause the index, or reference, dots to be made at the exact desired position on the chart. This framing adjustment having been once made, the index dots made in successive cycles of operations will form a straight vertical line at the left hand side of the chart. The motor-speed-indicating dots will then form two vertical lines at the other side of the chart so long as the speed of the recorder motor 101 is in synchronous relationship with the speed of the driving motor of the radio-meteorograph transmitter. Any variation in the proper relative speeds of these two motors will be indicated by departure of these motor-speed-indicating dots from a vertical line. This variance from the proper relative speeds of the two motors may then be corrected by adjustment of the speed of the recorder motor. The recorder is therefore provided with means for adjustably varying the speed of its driving motor 101.

The synchronizing, or motor-speed-adjusting, means of the illustrated apparatus is shown in Figs. 1 and 2. The adjustment is effected by adjustment of the motor governor 160 by means of a rod 161 mounted at one end to turn in a bearing block 162 and having its other end threaded and mounted in a threaded opening in a block 163. The rod will thus be moved longitudinally in one direction or the other when turned in one direction or the other, and by this longitudinal movement of the rod the governor may be adjusted to increase or decrease the speed of the motor 101 as required to restore synchronism. A click wheel 164 engaged by a click spring 165 holds the rod against unintended turning, and the clicks indicate to the operator a predetermined speed adjustment, thereby enabling the operator to make the required speed adjustment indicated by a departure of the speed indicating dots on the chart from a vertical line. The rod 161 is turned for adjusting the motor speed by means of a knob 166 carried by a shank which extends downward through the mounting plate 10 and has at its lower end a bevel gear 167 meshing with a bevel gear 168 on a hub mounted on the end of rod 161 and keyed thereto by a pin 169 extending into a longitudinal slot 170 in the rod, so that when the synchronizing knob 166 is turned, rod 161 is turned by the pin 169, the rod being free to move longitudinally because of its slot connection with the pin.

In addition to holding the governor adjusting rod against unintended turning, the click wheel 164 and spring click 165 serve the further important purpose of indicating to the operator the amount of speed adjustment made when he turns the knob 166, each click corresponding to a change in motor speed bearing a definite relationship to a certain observable departure of the motor-speed-indicating marks made on the record sheet from a straight vertical line. The operator can thus, by noting the click when he turns the speed adjusting knob, quickly make a required adjustment of the motor speed.

The electric wiring of the apparatus of Figs. 1 to 10 is shown in Fig. 11. The double-pole on-off switch 155 is connected to an alternating current

power source by means of conductors 180 which may enter the cabinet through a grommet 181 (see Figs. 1 and 2). From the apparatus side of this switch, conductors 182 supply the motor 101 with current, and as this motor is of the series type and equipped with a governor, a resistor 183 and a condenser 184 are connected across the governor contacts by means of conductors 185 and 186. A small step-down transformer 190 is also connected to the apparatus side of the on-and-off switch by means of conductors 191, and the low voltage secondary of the transformer is connected to a full wave copper oxide rectifier 192 by conductors 193. Across the output or D. C. side of the rectifier 192 there is connected a smoothing or filter condenser 194 which reduces the alternating current ripple from the rectifier in the well-known manner. The rectifier is connected by wire 195 to one of a pair of binding posts 196, and by wire 197, windings of magnet 78 and wire 198 to the other binding post 196. Connection is made from the binding posts 196 by conductors 200 to the relay of the radio receiver (not shown). Current is thus caused to flow through the windings of magnet 78 whenever the contacts of the radio receiver relay are closed. Magnet 78 may also be operated by means of a local operation switch 201 connected across the binding posts 196.

30 A paper cut-off groove 210 is provided in the top surface of the mounting plate 10 for convenience in cutting off a completed part or any desired portion of the record sheet, as by means of a wheel cutter 211 which when not in use may be releasably secured to the inside of the cover of the cabinet by means of a spring clip 212.

35

40 While most desirably and as in the machine shown, a flat record sheet, or chart, is fed forward in a straight line direction beneath the stylus, features of the invention might obviously be embodied in circular chart recorders or in drum-type chart recorders, in both of which, as in the strip chart recorder shown, the record sheet is fed transversely of the traversing movements of the stylus.

45

What is claimed is:

1. A recorder, comprising a stylus mounted for traversing forward and back across a record sheet and movable toward the record sheet, and means for causing the stylus to make record-making engagement with the record sheet while making its forward traversing movement, said means comprising a member by movement of which the stylus is moved toward the record sheet and the movement of which stops before the stylus has been moved into contact with the record sheet, the stylus being then free to continue movement by its own inertia into contact with the record sheet, and means for immediately retracting the stylus from the sheet.

2. A recorder, comprising a stylus mounted for traversing forward and back across a record sheet and movable toward the record sheet against spring tension, and means for causing the stylus to make record-making engagement with the record sheet while making its forward traversing movement, said means comprising a member by movement of which the stylus is moved toward the record sheet and the movement of which stops before the stylus has been moved into contact with the record sheet, the stylus being then free to continue movement by its own inertia into contact with the record sheet and being then immediately retracted from the sheet by said spring tension.

3. A recorder, comprising a slideway, a stylus carriage mounted on said slideway for traversing forward and back across a record sheet, a stylus carried by an arm extending from said carriage, said carriage being pivotally mounted on the slideway for movement of the stylus toward and from the record sheet, a spring-pressed member carried by the stylus arm to engage the record sheet and press the stylus away from the sheet, means for giving a limited rocking movement to said slideway, said slideway having a part for engaging the stylus carriage to move the stylus toward the record sheet when the slideway is rocked, the rocking movement of the slideway being stopped before the stylus has been moved into contact with the record sheet, the stylus being then free to continue movement under the inertia of the stylus arm into contact with the record sheet and being then immediately retracted from the sheet by said spring-pressed member.

4. A recorder, comprising a stylus mounted for traversing forward on a printing stroke and back on a non-printing return stroke across a record sheet, motor driven means for traversing the stylus, and means driven by the stylus traversing means for feeding the record sheet during the whole of each successive non-printing return stroke of the stylus and for holding the sheet stationary during the printing stroke of the stylus.

5. A recorder, comprising a slideway, a stylus carriage mounted on said slideway, a feed roll for feeding the record sheet, motor driven means for traversing the carriage forward and back on the slideway, means for causing the stylus to make record making engagement with the record sheet while making its forward stroke, means driven by the carriage traversing means for turning the feed roll to feed the record sheet forward during each successive non-printing return stroke of the carriage, and for holding the feed roll against rotation during the printing stroke of the carriage, said means including driving means and a driving worm and a friction clutch between the feed roll and the worm, and means for turning the feed roll manually to feed the record sheet forward or back at will.

6. A recorder, comprising a slideway, a stylus carriage mounted on said slideway, a feed roll for feeding a record sheet transversely of the traversing movements of the stylus carriage on the slideway, means for traversing the carriage forward and back on the slideway comprising a cord extending in opposite directions from the carriage and guiding means for said cord including a driving drum about which the cord is wound and means for driving said drum alternately in one direction to drive the carriage forward on its printing stroke and in the opposite direction to return the carriage to starting position, a pulley about which said cord turns, and one-way driving means between said pulley and the feed roll whereby when the pulley is turned in one direction the feed roll is turned to feed the record sheet and when the pulley is turned in the other direction the feed roll is not turned.

7. In a time interval signal recorder having a stylus mounted for traversing forward and back across a record sheet and for record making movement: means for holding the stylus against forward movement at its starting position, means for moving the stylus when released forward across the record sheet and back to its starting position, and a single magnet for releasing the stylus and for giving the stylus separate record

marking movements at the beginning, during, and at the end of its forward movement.

8. In a time interval signal recorder having a stylus mounted for traversing forward and back across a record sheet and for record making movement: driving means for giving the stylus its traversing movements including a friction clutch through which the stylus is moved forward on its printing stroke, means for holding the stylus at its starting position against forward movement by said driving means, and a single magnet for releasing the stylus on receipt of a starting impulse and for giving the stylus its record marking movements.

9. In a time interval signal recorder having a stylus mounted for traversing forward and back across a record sheet: driving means for giving the stylus its traversing movements including a friction clutch through which the stylus is moved forward on its printing stroke, a latch past which the stylus moves on its return movement positioned to hold the stylus at its starting position against forward movement by said driving means, and means for causing the stylus to make a reference mark on the record sheet and simultaneously releasing it from said latch.

10. In a time interval signal recorder having a stylus carriage mounted on a slideway for traversing forward and back across a record sheet: means for rocking the carriage to cause the stylus to make a mark on the record sheet, driving means for giving the carriage its traversing movements including a friction clutch through which the carriage is moved forward on its printing stroke, and a latch for holding the carriage at its starting position against forward movement by said driving means and from which latch the carriage is released by the rocking of the carriage to cause a mark to be made on the record sheet at the starting position of the carriage.

11. A time interval signal recorder as claimed in claim 10, in which said latch is adjustable to vary the starting position of the carriage and thereby to adjust the position on the record sheet of said starting position marks.

12. In a time interval signal recorder having a stylus carriage mounted on a slideway for traversing forward and back across a record sheet and having a forwardly extending stylus arm: means for rocking the carriage to cause the stylus to make a mark on the record sheet, driving means for giving the carriage its traversing movements including a friction clutch through which the carriage is moved forward on its printing stroke, a latch dog on the stylus arm, and a latch for engaging said dog to hold the carriage at its starting position against forward movement by said driving means and from engagement with which latch said dog is moved when the carriage is rocked to mark the record sheet at the starting position of the carriage, whereby the carriage is released simultaneously with the marking of the sheet and the beginning of the printing stroke of the carriage.

13. In a time interval signal recorder having a stylus carriage mounted on a slideway: means for traversing the carriage forward and back across the record sheet, said traversing means comprising a constantly operating motor, a rotary member driven by said motor, a second rotary member frictionally driven by the first said rotary member, a driving abutment on the second said rotary member, a third rotary member mounted coaxially with the second said rotary member, a movable latch member carried

by said third rotary member movable into and out of position to be engaged by said driving abutment, means for moving said latch member out of engagement with said driving abutment after the third said rotary member has been given a predetermined rotation, a spring for returning the third said rotary member to its starting position when released from said driving abutment, means for returning said latch member to its engaging position, and a driving connection between said third rotary member and the stylus carriage whereby the stylus carriage is moved forward on its printing stroke when the third said rotary member is turned by said abutment and is given a rapid return stroke by the spring return movement of the third said rotary member.

14. In a time interval signal recorder having a stylus carriage mounted on a slideway: means for traversing the carriage forward and back across the record sheet, said traversing means comprising a driving element, a driving member extending from the stylus carriage to said element, a driving motor, and driving connections between the motor and said element including a friction clutch and a rotary member driven through the friction clutch and a second rotary member by which said element is operated to move the carriage forward on its printing stroke, and means whereby on each rotation of the first said rotary member the second said rotary member is given a predetermined rotation and then released, and spring means for causing rapid return movement of the carriage when said second rotary member is released from said first rotary member.

15. In a time interval signal recorder having a stylus carriage mounted on a slideway: means for traversing the carriage forward and back across the record sheet, said traversing means comprising a frictionally driven rotary member, a second rotary member by which the carriage is given its forward and back traversing movements mounted coaxially with the first said rotary member, a driving dog on the first said rotary member, a pivoted latch member carried by the second said rotary member movable into and out of position to be engaged by said driving dog, said latch member having a part extending through an opening in the second said rotary member, an abutment by engagement of said latch member part with which when the second said rotary member has been turned a predetermined amount by the first said rotary member the latch member is moved out of engagement with said driving dog, a spring for turning the second said rotary member backward when released from the first said rotary member, and an abutment with which said latch member part engages to shift the latch member back to engaging position and to stop the backward rotation of the second said rotary member at its starting position.

16. A time interval signal recorder as claimed in claim 15, in which the abutments engaged by said latch member part are the opposite sides of a pivoted arm the free end of which is connected to a dash pot member, whereby the stopping of the backward rotation of the second said rotary member is cushioned, said arm being moved by said latch member part against spring tension

by which the arm and dash pot member are returned to normal position when the second said rotary member is being turned by the first said rotary member.

- 5 17. In a time interval signal recorder adapted to make a record in response to signal impulses which in each of successive cycles include first a starting signal impulse, then one or more condition-indicating signal impulses, and finally a 10 motor-speed-indicating signal impulse: a stylus mounted for traversing forward and back across a record sheet, means for operating the stylus to make marks on the record sheet in response to said signal impulses, a motor for driving the stylus 15 on its forward printing strokes, a governor for maintaining the speed of said motor constant, means for causing the motor to become effective to move the stylus forward on receipt of a starting signal impulse, and means for adjusting the 20 governor to vary the speed of the motor to correct any variation from the desired speed as indicated by the markings made on the record sheet by the stylus in response to the motor-speed-indicating impulses.
- 25 18. In a time interval signal recorder adapted to make a record in response to signal impulses which in each of successive cycles include first a starting signal impulse, then one or more condition-indicating signal impulses, and finally a 30 motor-speed-indicating signal impulse: a stylus mounted for traversing forward and back across the record sheet, means for feeding the record sheet transversely of the traversing movements of the stylus, a motor for moving the stylus 35 on its successive forward printing strokes, means for causing the motor to become effective to move the stylus forward on receipt of a starting signal impulse, electromagnetic means responsive to signal impulses for moving the stylus during its forward strokes into momentary marking engagement with the record sheet, and means for adjusting the speed of the motor to correct any variation from the desired speed as indicated by the marks made on the record sheet by the 40 stylus in response to the motor-speed-indicating impulses.
- 45 19. In a time interval signal recorder adapted to make a record in response to signal impulses which in each of successive cycles include first a starting signal impulse, then one or more condition-indicating signal impulses, and finally a 50 motor-speed-indicating signal impulse: a stylus mounted for traversing forward and back across the record sheet, means for feeding the record sheet transversely of the traversing movements of the stylus, means for moving the stylus on its successive forward printing strokes comprising a motor and a driving train including a friction clutch, electromagnetic means responsive to 55 signal impulses for moving the stylus into momentary marking engagement with the record sheet, means for holding the stylus against forward movement at its starting position and for releasing the stylus in response to the starting signal impulse whereby a reference mark is made on the record sheet at the start of each printing stroke of the stylus, and means for adjusting the 60 speed of said motor to correct any departure of the motor-speed-indicating record on the sheet from a straight vertical line.
